UNITED STATES PATENT OFFICE.

FRANK D. RIFNER, OF DAYTON, OHIO.

PRESS-DIE.

1,388,374.

Specification of Letters Patent. Patented Aug. 23, 1921.

Application filed January 29, 1920. Serial No. 355,012.

To all whom it may concern:

Be it known that I, FRANK D. RIFNER, a citizen of the United States, residing at Dayton, in the county of Montgomery and State of Ohio, have invented certain new and useful Improvements in Press-Dies, of which the following is a specification, reference being had therein to the accompanying drawing.

10 This invention relates to press dies and has for its particular object to provide die mechanism of improved construction which may be operated with relatively less power, and in which the coöperating parts will retain their normal relation to each other a longer time than die mechanism constructed under the common practice.

15 It is common practice in dies of this character to interpose springs or cushions of rubber between the die members having movement relative to each other to maintain their normal relation and to relieve the shock of the punching or forming operation for which the dies are used and to restore the parts to 20 their normal relation after each operation.

25 It is well known in the trade that a great amount of power is required, where the work is heavy and the dies are accordingly large, to overcome the resistance of the resilient elements between the die members in the working stroke of the punch or forming press; also that the resilient elements when 30 constituted of the usual compression springs or of rubber cushions become set, or lose 35 more or less of their resiliency with use so that the relation of the die members one to the other becomes abnormal to such extent that the die will not function properly.

35 The purpose of the present invention is 40 to overcome these common defects of construction by providing positive mechanical means to perform the function of the resilient elements and which will be effective to greatly reduce the power required to operate the dies and which will not be subject 45 to the variations caused by deterioration of the resilient elements used in ordinary construction.

Furthermore, my improved die mechanism 50 is of simple construction, positive in operation, cheap to manufacture and practically indestructible. It can be applied to dies of ordinary construction and to punch presses of the usual commercial types.

Also the mechanism when once installed 55 on a punch press is readily adaptable to dies for different products, the mechanism thus being capable of being standardized and furnished as part of the equipment of commercial punch presses. The mechanism may 60 also be applied to punch presses already in use. Thus, the advantages of the invention are available to manufacturers for punch presses already in use or as equipment of new presses to be installed.

65 As far as I am aware the principle of my invention is broadly new in this art. I desire, therefore, to claim the invention broadly without reference to specific details, and also 70 to claim the invention specifically, as defined and comprehended in the appended claims.

75 In the accompanying drawings, a preferred form of construction of the invention is shown for illustrative purposes. As here shown, the objects of the invention are realized in a simple practicable manner, but it will be obvious to those skilled in the art that various modifications of construction and arrangement may be made without materially affecting either the manner or result 80 of operation or departing from the principle and spirit of the invention.

85 In the accompanying drawings; Figure 1 is a detail vertical sectional view of a portion of a punch press to which my invention has been applied;

90 Fig. 2 is a perspective view of the mechanism comprised in the invention detached from the press; and

95 Fig. 3 is a longitudinal sectional view. The invention is here shown as applied to a punch press of a well known commercial type consisting of the base frame 1, body frame 2, bed plate 3 and ram 4. Other details of the press construction are not required to illustrate the invention and are, therefore, not shown.

100 The invention is shown for illustrative purposes as used in connection with a well known type of forming die, but it will be understood that its use is not limited to any particular type of die but may be used with the full advantages of the invention with the general types of blanking, forming and drawing dies or their usual combinations.

105 The usual bolster 5 as here shown is secured to the bed plate 3. The male member or forming head 6, secured in a supporting

plate 7, is mounted on the bolster 5, a pressure plate or stripper ring 8 coöperating with the head 6 in the usual manner.

The female member or forming die 9 is carried by the ram 4 being secured thereto in the usual manner by a die holder 10. These features are all well known in common practice.

As shown in Fig. 1 a sub-base plate 11 is secured on the under side of the bolster 5, a suitable aperture being provided in the bed plate of the press to admit the sub-plate, and the connection being made in any suitable manner. Secured in the sub-plate, at 15 the opposite corners thereof, as here shown, are vertical guide shafts 12, extending downwardly from the plate 11 a considerable distance into the base of the press. Also secured to the plate 11 and extending downwardly from the opposite ends thereof are cam plates 13, the purpose and operation of which will presently be described.

Mounted upon the guide shafts 12 are upper and lower vertically reciprocating plates 25 14 and 15, respectively, which are joined together at their opposite ends by toggle levers 16 and 17, the upper lever 17 having a stud or roller 18 coöperating with a cam 19 in the plates 13. The lower plate 15 is connected 30 to the ram of the press by two opposite suspension and adjusting rods 20 and is therefore actuated in a vertical plane the full stroke of the press at each operation thereof. Both plates 14 and 15 have a sliding connection with the cam plate 13.

The upper extension 21 of the cam 19 is on the arc of a circle on a radius from the pivot center 22 of the toggle lever 17, the lower extension of the cam 23 being parallel to 40 the vertical sides of the cam plate. Thus during the initial movement of the plate 15 upon the down stroke of the ram the plate 14 remains stationary, the toggles expanding to compensate for the increasing distance 45 between the two plates 14—15 until the stud 18 passes out of the arc 21 of the cam into its straight extension 23 whereupon both plates 14—15 will move equally to the completion of the down stroke of the press. On 50 the up stroke of the press the conditions are just the reverse from those described, *i. e.*, the two plates will move equally until the stud 18 passes from the straight cam into the arc, whereupon the upper plate will be 55 restored to stationary position and the lower plate will continue its movement to the completion of the up stroke.

The ring plate 8 is supported upon the plate 14 by means of rods 24 extending 60 through suitable apertures in the plates 5, 7 and 11, the rods having free contact at their opposite ends with the ring 8 and plate 14. In the normal relation of the parts, when the plate 14 is in its uppermost position the ring plate 8 will be substantially

flush with the upper surface of the forming head 6 and will act to support during the forming operation the edges of the strip or blank of metal 25 of which the product is to be formed.

During the initial downward movement of the ram, until the die 9 comes in easy contact with the blank 25, the stud 18 of the shackle levers will travel through the arc of the cam, the plate 14 therefore remaining at 70 rest. With the beginning of the forming operation the stud 18 will enter the straight portion of the cam and the plate 14, ring 8 and rods 24 will move equally with the ram and plate 15 to the completion of the forming stroke.

The product thus formed will be in contact at its lower edge with the ring 8, the tendency of the product being to spread outwardly more or less at its edge over the 85 top of the ring. Thus upon the up stroke of the press the ring will act as a stripper for the forming head 6 and the product will be removed therefrom upon completion of the operation.

By means of the threaded shafts 20 and adjusting nuts 26 the lower plate 15 may be readily raised or lowered on the shafts 12 and relative to the plate 14 to adjust the shackle stud 18 relative to the cam 19 to 95 compensate for wear or to take up lost motion of the parts; also to adjust the depth of the draw or form.

It will be observed that the improved die mechanism, as best shown in Fig. 2, is a 100 self-contained unit, that is to say, the mechanism is so interrelated that it constitutes a unit of assembly, and is adapted to be mounted on a press in its assembled form.

The operation of my improved press die is 105 apparent. The metal blank 25 is placed on the ring 8. The forming die 9, is then forced down until it comes into contact with the metal blank before the ring 8 begins to move. Plate 15 is also carried down with die 9. 110 During this downward movement of the forming die 9 and plate 15, the plate 14, ring 8 and metal blank remain stationary, the toggles 16 and 17 expanding thus allowing the necessary increased distance between the 115 two plates 14 and 15. Just as the forming die 9 reaches the metal blank the stud 18 will pass out of the arc 21 of the cam into the straight extension 23 and cause both plates 14—15 together with ring 8 to be carried down with forming die 9 when the stationary head 6 will press the plate into the female member 9 thus drawing the metal blank into the desired shape as the forming die 9 moves downwardly with the ring 8 over 125 the stationary head 6. The forming member 9 and ring 8 are then in the further operation of the press moved upwardly together, Fig. 1, the latter stripping the formed article from the head 6 as the parts rise until 130

the ring 8 reaches the position shown in Fig. 1, the forming die 9 continues to move upwardly being permitted to do so by the breaking of the toggles until 9 reaches the 5 position shown in Fig. 1. In this position the ring 8 will have stripped the article off the head 6 and raised it to the position of ring 8 in Fig. 1. The article is then removed and another blank placed on the ring 10 8 and this operation may be repeated indefinitely.

From the illustrations of the drawings and the foregoing detailed description the construction, operation and results of operation 15 of the invention will be readily understood by those experienced in this art.

Having thus fully described my invention, what I claim as new and desire to secure by Letters Patent, is:—

20 1. In a die mechanism a fixed die member, a movable die carried by the ram of the press, a movable member coöperating with the fixed die to hold the material, a member carried by the ram, and a fixed cam and connections for causing said movable member to remain stationary during the first part of the ram's motion and to follow it, to thus first hold on and then to strip off the material from the fixed die as described.

30 2. In a die mechanism a fixed die member, a movable die carried by the ram of the press, a movable member coöperating with the fixed die to hold the material, a member carried by the ram, and members rigidly attached to the fixed die and carrying cams, and connections between the cams and said movable member to cause the latter to remain stationary during the first and last 35 part of the ram's motion and to follow it, to first hold on and then to strip off the material from the fixed die as described.

3. In a die mechanism, a fixed die member, a movable die carried by the ram of the press, a movable member coöperating with the 45 fixed die to hold the material, a member carried by the ram, and members rigidly attached to the fixed die and carrying cams, and toggle levers between the cams and said movable member to cause the latter to remain stationary during the first and last 50 part of the ram's motion and to follow it, to first hold on and then to strip off the material from the fixed die as described.

4. In die mechanism, the combination, 55 with a die member mounted in fixed relation on the frame of a press, and a coöperating die member carried by the ram of the press, of a movable member coöperating with the fixed die member, a fixed guide, a member 60 suspended from the ram and operable on said guide, and connections between the suspended member and said coöperating member whereby the latter will be caused to operate relative to the fixed die upon each stroke 65 of the press.

5. In die mechanism, the combination, with a die member mounted in fixed relation on the frame of a press, and a coöperating die member carried by the ram of the press, of a movable member coöperating with the 70 fixed die member, a plurality of guides extending downwardly from the fixed die, a member suspended from the ram and having reciprocal movement on said guides, and connections between the suspended member and 75 said coöperating member whereby the latter will be caused to operate relative to the fixed die upon each stroke of the press.

6. In die mechanism, the combination, with a die member mounted in fixed relation 80 on the frame of a press, and a coöperating die member carried by the ram of the press, of a movable member coöperating with the fixed die member, a plurality of guides extending downwardly from the fixed die, a 85 member suspended from the ram and having reciprocal movement on said guides, a member operable on said guides intermediate the suspended member and the fixed die, and connections between said parts whereby the 90 coöperating member will be actuated upon each stroke of the press.

7. In die mechanism, the combination, with a die member mounted in fixed relation 95 on the frame of a press, and a coöperating die member carried by the ram of the press, of a movable member coöperating with the fixed die member, a plurality of guides extending downwardly from the fixed die, a member suspended from the ram and having 100 reciprocal movement on said guides, a member operable on said guides intermediate the suspended member and the fixed die and having connections with the suspended member and said coöperating member whereby 105 the latter will be actuated upon each stroke of the press.

8. In die mechanism, the combination, with a die member mounted in fixed relation 110 on the frame of a press, and a coöperating die member carried by the ram of the press, of a movable member coöperating with the fixed die member, a plurality of guides extending downwardly from the fixed die, a member suspended from the ram and having 115 reciprocal movement on said guides, a member operable on said guides intermediate the suspended member and the fixed die and having connections with the coöperating member and with the suspended member, whereby the distance therebetween will be varied, and the coöperating member will be held stationary during a part and actuated during a part of the operating movement of 120 said ram.

9. In die mechanism, the combination, with a die member mounted in fixed relation 125 on the frame of a press, and a coöperating die member carried by the ram of the press, of a movable member coöperating with the 130

fixed die member, a plurality of guides extending downwardly from the fixed die, a member suspended from the ram and having reciprocal movement on said guides, a member operable on said guides intermediate the suspended member and the fixed die and having loose connections with said coöperating member, and compensating connections with said suspended member, whereby the co-
operating member will be held at rest during the initial and ending movements and actuated during the intermediate movement of the ram.

10. In die mechanism, the combination, with a die member mounted in fixed relation on the frame of a press, and a coöperating die member carried by the ram of the press, of a movable member coöperating with the fixed die member, a plurality of guides extending downwardly from the fixed die, a member suspended from the ram and having reciprocal movement on said guides, a member operable on said guides intermediate the suspended member and the fixed die and having loose connections with said coöperating member, and compensating connections with said suspended member, whereby the distance therebetween will be varied and the coöperating member will be held at rest during the initial movement, restored to rest preceding the final movement and reciprocated vertically during the intermediate movement of said ram.

11. In die mechanism, the combination, with a die member mounted in fixed relation on the frame of a press, and a coöperating die member carried by the ram of the press, of a movable member coöperating with the fixed die member, a stationary plate mounted in the vertical plane of the fixed die and having a plurality of guides secured therein and extending downwardly therefrom, a member suspended from the ram and having reciprocal movement on said guides, and connections between the suspended member and said coöperating member, whereby the latter will be caused to operate relative to the fixed die upon each stroke of the press.

12. In die mechanism, the combination, with a die member mounted in fixed relation on the frame of a press, and a coöperating die member carried by the ram of the press, of a movable member coöperating with the fixed die member, a stationary plate mounted in the vertical plane of the fixed die and having a plate with a cam secured thereto and extending downwardly therefrom, a member suspended from the ram and having reciprocal movement relative to the cam plate, and a member interposed between the suspended member and said stationary plate having connections with said coöperating member and with said suspended member, the latter connections coöperating with said cam to cause variable relations between the

suspended member and the intermediate member, whereby operating relation between the coöperating member and the fixed die is effected.

13. In die mechanism, the combination, with a die member mounted in fixed relation on the frame of a press, and a coöperating die member carried by the ram of the press, of a movable member coöperating with the fixed die member, a stationary plate mounted relative to the fixed die and having opposite plates with cams and a plurality of guides secured thereto and extending downwardly therefrom, a member suspended from the ram and having reciprocal movement relative to the cam plates and said guides, and a member interposed between the suspended member and said stationary plate having connections with said coöperating member and with said suspended member, the latter connection coöperating with said cam to cause variable relations between the suspended member and the intermediate member, whereby operating relation between the coöperating member and the fixed die is effected.

14. In die mechanism, the combination, with a die member mounted in fixed relation on the frame of a press, and a coöperating die member carried by the ram of the press, of a movable member coöperating with the fixed die member, a stationary plate mounted relative to the fixed die member and having opposite plates with cams and a plurality of guides secured thereto and extending downwardly therefrom, a member suspended from the ram and having reciprocal movement relative to the cam plates and said guides, and a member interposed between the suspended member and said stationary plate, being connected to said coöperating member by a plurality of vertically arranged loose bars, and to the suspended member by oppositely disposed toggle levers having operable connections with said cams, whereby operable relation between the coöperating member and the fixed die is effected.

15. In die mechanism, the combination, with a die member mounted in fixed relation on the frame of a press, and a coöperating die member carried by the ram of the press, of a movable member coöperating with the fixed die member, a stationary plate mounted relative to the fixed die and having a plurality of guides extending downwardly therefrom, oppositely disposed cams having variably directed courses therein arranged relative to said guides, a member suspended from said ram and having reciprocal movement relative to said guides and cams, a member interposed between the suspended member and the stationary plate, being loosely connected to said coöperating member, and to the suspended member by oppo-

- sitely arranged sets of toggle levers having operable relation with said cams, whereby operable relation between the coöperating member and the fixed die is effected.
- 5 16. In die mechanism, the combination, with a die member mounted in fixed relation on the frame of a press, and a coöperating die member carried by the ram of the press, of a movable member coöperating with the 10 fixed die member, a plurality of guides and a cam arranged relative to the fixed die, said cam having one end of its course arranged in an arc of a circle and its opposite end straight, a member suspended from said 15 ram and operable relative to said guides and cam, and a member interposed between the suspended member and the fixed die, having operable relation with the coöperating member and being connected to the suspended 20 member by oppositely arranged toggle levers operatively connected to said cam, whereby when said toggle connections are operated through the arc of the cam the coöperating member will be held in stationary 25 relation and when said connections are operated through the straight cam said member will be reciprocated relative to the fixed die.
17. In operating mechanism for dies, the 30 combination, with a stationary plate, a plurality of guides and oppositely disposed cam plates secured to and extending downwardly from said plate, and cams arranged in said plates, of a plurality of vertically reciprocating plates mounted on said guides, one above the other, and joined together by opposite sets of toggle levers, each set of levers having operable relation with one of said cams.
- 40 18. In operating mechanism for dies, the combination, with a stationary plate, a plurality of guides and oppositely disposed cam plates secured to and extending downwardly from said plate, and cams arranged in said 45 plates, of a plurality of vertically reciprocating plates mounted on said guides, one above the other, and having sliding connection with the cam plates, said reciprocating

plate being joined together by opposite sets of toggle levers, each set of levers having 50 operable relation with one of said cams.

19. In operating mechanism for dies, the combination, with a stationary plate, a plurality of guides and oppositely disposed cam plates secured to and extending downwardly 55 from said plate, and cams arranged in said plates, of a plurality of vertically reciprocating plates operable on said guides, one above the other, and joined together by toggle levers having operable connections with 60 said cams, whereby the distance between said plates will be varied upon operation of said mechanism.

20. In operating mechanism for dies, the combination, with a stationary plate, a vertically disposed guide and a cam plate extending downwardly from said stationary plate, and a variable cam carried by the cam plate, of a plurality of reciprocating plates operable on the guide and joined together 65 by toggle levers having operable relation with said cam, whereby said plates will be caused to have relative movement to each other and to move equally at different times in a single operation of said mechanism. 70

21. In operating mechanism for dies, the combination, with a stationary plate, a vertically disposed guide and a cam plate extending downwardly from said stationary 80 plate, of a variable cam carried by the cam plate, said cam having an extension in the arc of a circle and a straight extension, and a plurality of reciprocating plates operable on said guide, one above the other, said 85 plates being connected one to the other by toggle levers having an operable connection with said cam, whereby one of said plates will be maintained at rest while the other is moving during the passing of said connection through the arc of the cam and both plates will move equally during the passing of the connection through the straight extension of the cam. 90

In testimony whereof, I affix my signature. 95
FRANK D. RIFNER.
